TOY REPEATING RUBBER BAND GUN

John R. Crnich, Chicago, Ill.

Application June 30, 1945, Serial No. 602,534

3 Claims. (Cl. 124—19)

1

The present invention relates to toy guns and has for its object the provision of an improved gun for discharging in succession rubber bands as missiles.

A still further object of the present invention is the provision of a gun of the type indicated and wherein rubber bands may be stretched upon the barrel and dislodged from their stretched condition by suitable means for discharging said rubber bands in succession.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views;

Fig. 1 is a side elevational view of the toy gun;
Fig. 2 is a top elevational view thereof;

Fig. 3 is a cross-sectional view on line 3—3 of Fig. 1;

Fig. 4 is a cross-sectional view on line 4—4 of Fig. 2; and

Fig. 5 is a similar view showing the rubber band dislodging means in a different position.

Referring to the present drawing in detail there is shown a gun including a butt 10, stock 11, and barrel 12. Said stock 11 is formed of a pair of spaced plates 13, which may be integrally formed with said butt 10 and barrel 12.

Said plates 13 adjacent their upper edges are provided with a plurality of alined teeth 14 and the resultant notches 15. Barrel 12 is provided with a transverse horizontally disposed groove 16 at its free end. Rubber bands 17 are each engaged within alined notches 15 in the two plates 13 and said groove 16. Each of said rubber bands bears against the alined teeth 14 and is in a stretched condition.

In order to dislodge said rubber bands 17 from within their respective notches 15, for the purpose of discharging the same, a suitable mechanism is provided and includes sliding plate 18 positioned between plates 13 for longitudinal shifting movement. Said plate 18 is provided with a pair of longitudinally disposed slots 19, within each of which pin 20, passing through said plates 13, is located. Thus, said slots 19 and pins 20 constitute guiding means for said plate 18, permitting the longitudinal movement of said plate within stock 11.

2

Said sliding plate 18 is further provided with lug 21, extending from the upper edge of said plate 18, said lug 21 extending above the upper edge of said plate 18 and above the upper edges of said plates 13. Said lug 21 has an inclined rear wall 22, which, bearing against the portion of rubber band 17, stretched between a pair of alined teeth 14 in two plates 13, and resting within the adjacent notch 15, as is clearly seen in Fig. 3, 10 acts as a wedge for elevating the rear end of rubber band 17 from the alined teeth 14, as said inclined wall 22 rides rearwardly when said plate 18 is shifted into the same direction. The action of said inclined wall 22 of lug 21 hereinabove 15 described, shifts the rear end of rubber band 17 upwardly and along the rear faces of a pair of alined teeth 14 with which the same was theretofore in engagement, the rubber band thereupon being propelled away from the gun and in the 20 direction to which barrel 12 points.

Shifting movement of sliding plate 18 aforesaid is accomplished manually by engaging operator's finger with one of a series of finger openings 23 which are arranged in a row adjacent the 25 lower edge of said plate 18. Adjacent the lower edge each of said plates 13 is provided with recess 24 which permits at least two of said finger openings 23 to be located therewithin at a given time, as is indicated in Fig. 4. When the rearmost 30 opening 23 is engaged and plate 18 shifted as far as the rear edges of said recess 24 will permit, position indicated by dotted lines in Fig. 4, the frontmost rubber band shall have been discharged. When this has been accomplished, the adjacent 35 opening 23 is shifted into recesses 24 and adjacent the front edges thereof, ready to be engaged by an operator's finger for further shifting of plate 18 rearwardly for dislodging the second rubber band. This operation is repeated until all of the 40 rubber bands have been discharged. It is observed that there is a predetermined co-relation between the inclined face 22 of lug 21 and openings 23, on one hand, with recesses 24, on the other. It requires shifting of plate 18 only to 45 such an extent as is required to bring a given opening 23 from its forward position within recesses 24 to its rearward position with relation therewith in order to dislodge a single rubber band 17 from its engagement with an alined 50 pair of teeth 14.

It is observed that since the rubber band which is engaged at the frontmost teeth 14 will be the first one to be discharged by operation of plate 18, it is necessary to engage the same last with said 55 frontmost teeth 14 and barrel 12.

While here is described herein a preferred embodiment of the present invention, it is nevertheless to be understood that minor changes may be made therein without departing from the spirit and scope of the invention as claimed.

What I claim as new is:

1. A toy gun for shooting elastic bands comprising a pair of spaced plates, said plates defining a stock of the gun, a barrel connected to said plates, a plurality of alined teeth upon said plates, each pair of aligned teeth being shaped to hold an elastic band which is engaged in a stretched condition over said barrel, a sliding plate positioned between said first named plates, a lug integrally formed with said sliding plate and extending beyond said teeth, said lug being provided with an inclined face for the purpose of disengaging said elastic bands from said teeth in succession for propelling the same when said sliding plate is shifted within said stock, said plates of said stock being provided with alined recesses, said sliding plate being provided with a plurality of finger openings arranged in a row and in the path of said recesses, said finger openings constituting means whereby said sliding plate may be engaged for shifting the same, and means cooperating with said plates and said sliding plate whereby the shifting of the latter plate may be periodically limited to the extent required for said lug to dislodge a single elastic band from the pair of said teeth with which the same is in engagement.

2. A toy gun for shooting elastic bands comprising a butt, a pair of spaced plates connected therewith, said plates defining a stock of the gun, a barrel connected to said plates, a plurality of alined teeth upon said plates, each pair of aligned teeth being shaped to hold an elastic band which is engaged in a stretched condition over said barrel, a sliding plate positioned between said first named plates, and a lug integrally formed with said sliding plate and extending beyond said teeth, said lug being provided with an inclined face for the purpose of disengaging said elastic bands from said teeth in succession for propelling the same when said sliding plate is shifted within said stock, said plates of said stock being provided with alined recesses, said sliding plate being provided with a plurality of finger openings arranged in the path of said recesses, said recesses defining edges in the body portion of said stock plates which are disposed adjacent said barrel and like oppositely disposed edges adjacent said

butt, no more than two of said finger openings being accommodated at any time within said recesses and between said edges, when the operator's finger is engaged at the finger opening nearest to the first named edges for shifting said sliding plate in the direction of said butt the inclined face of said lug disengaging the elastic band from the pair of foremost of said teeth for propelling the same, the last mentioned shifting of said sliding plate bringing said last mentioned finger opening to the proximity of said second named edges, the operator's finger coming in contact with said second named edges preventing further shifting movement of said sliding plate, the last mentioned shifting of said sliding plate being adapted to simultaneously shift the next of said finger openings within said recesses and adjacent said first mentioned edges for conditioning said lug for action upon the next of said elastic bands when the operator's finger is engaged at said last mentioned finger opening for repeated shifting of said sliding plate.

3. A toy gun for shooting elastic bands comprising a pair of spaced plates, said plates defining a stock of the gun, a barrel connected to said plates, a plurality of alined teeth upon said plates, each pair of aligned teeth being shaped to hold an elastic band which is engaged in a stretched condition over said barrel, a sliding plate positioned between said first named plates, a lug carried by said sliding plate and extending between and beyond said teeth, said plates of said stock being provided with alined recesses, said sliding plate being provided with a plurality of finger openings arranged in a row and in the path of said recesses, said finger openings constituting means whereby said sliding plate may be engaged for shifting the same, and means cooperating with said plates and said sliding plate whereby the shifting of the latter plate may be periodically limited to the extent required for said lug to dislodge a single elastic band from the pair of said teeth with which the same is in engagement.
